UNITED STATES PATENT OFFICE

EDWARD ROSCOE BLACK, OF CHICAGO, ILLINOIS, ASSIGNOR TO BLACK SYSTEMS INC., OF CHICAGO, ILLINOIS, A CORPORATION OF ILLINOIS

BUILDING COVERING

Application filed May 2, 1929. Serial No. 359,756.

My invention relates to building coverings, and is particularly concerned with flexible roofing and siding such as individual, strip and roll shingles, ridge strips, gutter strips, 5 flushings and so called "roll-roofing".

One of the objects of the invention is to provide an improved covering construction which is of universal application to substantially all forms of flexible roofing or 10 siding units.

Another object is to provide an improved covering unit in which the exposed portion of each unit is anchored to the building framework without any exposed metal.

15 Another object is to provide an improved building covering wherein the shingles or units may be attached to the building framework independently of each other adjacent the exposed edges of the units by means of 20 ordinary roofing nails.

Another object is to provide an improved roof covering and the like in which the shingles or units may be secured to the roof at both the exposed and covered edges of the 25 units with ordinary nails, without exposing the nails to the weather.

Another object is to provide an improved mode of attachment of roofing to a building framework, which is applicable to individual 30 shingles, plural unit shingles, roll shingles, roll roofing, ridge strips, gutter strips, corner strips or other forms of flexible units.

Another object is to provide an improved roofing construction in which certain parts of 35 the roofing are adapted to provide a shading effect or a contrasting color effect for enhancing the appearance of the finished roof.

Another object is to provide an improved covering having an integral portion permanently folded back to receive a securing nail or the like, in such manner that the nail will 40 be concealed and protected by the roofing.

Another object is the provision of an improved covering construction having attaching 45 portions which are accessible for nailing or the like, without the necessity for bending said attaching portions in the nailing operation, thereby avoiding breaking of the roofing by frequent bending at the folded 50 portions.

Another object is the provision of an improved covering construction in which the unit may be prefolded to form attaching portions, that is, the flexible roofing may be folded over while hot so that the folding 55 operation does not tend to break the roofing at the point of the fold, as might be the case where the roofing is folded while cold at the time it is attached to the building.

Another object is to provide an improved building covering construction which can be laid with a minimum expenditure of time and labor and secured with ordinary roofing nails for positively preventing curling of the lower 60 edges.

Other objects and advantages will herein-after appear.

Several typical embodiments and adaptations of the invention are illustrated in the accompanying drawings wherein:

Fig. 1 is a view in perspective of the invention as applied to a ridge strip upon a roof;

Fig. 2 is an enlarged detail view of a pair of such ridge strip units, in the position which they assume when applied to the ridge, but having their ends slightly separated and portions broken away to show the structure;

Fig. 3 is a plan view showing the ridge strip pattern of Figs. 1 and 2;

Fig. 4 is a plan view of a portion of a roof covered with plural unit shingles constructed according to the present invention, with the improved feature of shading or color contrast;

Fig. 5 is a view in perspective of one of the plural unit shingles shown in Fig. 4;

Fig. 6 is a plan view of one of the same units showing the pattern for the unit;

Fig. 7 is a plan view of a portion of a roof equipped with rectangular flexible shingles laid diagonally;

Fig. 8 is a detail view of one of the shingles of Fig. 7;

Fig. 9 is a plan view of a portion of a roof 95 equipped with ordinary rectangular shingles of a modified form, laid in horizontal courses;

Fig. 10 is a plan view of the pattern for the shingles used in Fig. 9;

Fig. 11 is a plan view of a modified form of the same shingles shown in Figs. 9 and 10.

The terms "shingles" or "units" in the following specification and claims are to be understood to include all of the forms of flexible roofing, siding, or other building covering, to which the improved features of the invention may be applied, such as individual shingles, plural unit or strip shingles, roll shingles, roll roofing or siding, ridge strips, gutter strips, corner strips or the like, and I do not wish to be limited to any specific form or adaptation except as set forth in the appended claims. However, in the following description, the various embodiments of the invention will be explained as applied to roof coverings, since from such description its other adaptations will be readily understood.

Referring to Figs. 1 to 3, 20 indicates an ordinary roof which may be covered with roofing 21 of any of the usual forms or of any of the improved types described herein-after. In the present embodiment, the roofing 21 comprises ordinary roll roofing, the edges of which have been formed in accordance with the present invention.

The major portion of the roof having been covered with suitable roofing, the ridge of the roof may be covered by means of a plurality of ridge strip units 22, 23, 24. The ridge strip units 22 to 24 are adapted to be secured to the roof by ordinary roofing nails in such manner that the strips overlap each other and overlap the roofing previously applied, protecting and covering the nails which secure the ridge strips and the other roofing.

Referring to Fig. 3, it will be observed that the present embodiment of the covering unit or ridge strip comprises a substantially rectangular sheet of flexible prepared roofing and in the case of ridge strips, the unit is preferably of considerably greater length than breadth. The sheet 23 is provided with a plurality of slits indicated in their entirety at 25, for the purpose of forming one or more bendable portions or flaps 26 in the roofing unit 23, to permit access to the underlying space for the application of nails or other fastening means used to secure the strip in place.

The flaps 26 of the roofing unit 23 may of course take many different forms, so that the slits 25 need not be rectangular in shape, but they may be curved, triangular, hexagonal or of any other shape capable of providing a bendable portion or flap 26 in the roofing unit adjacent the edge or edges to be secured. In the present embodiment, the slits 25 are preferably formed with a longitudinally extending slit 27 and a pair of inwardly extending transverse slits 28 and 29 to form one or more flaps 26 whose function

will be hereinafter more particularly described.

Since a ridge strip, corner strip or gutter strip should preferably be secured adjacent both edges, the unit 23 is provided with similar slits 25 adjacent each of the lateral edges of the unit, but it should be understood that where only one edge of the roofing unit is to be secured, the slits will be formed only adjacent that edge, and in fact the slits and flaps may be provided wherever it is desired to provide a securing means for the roofing unit.

Referring to Fig. 2, in the present embodiment the roofing unit 23 is provided with a portion 30 which is folded back or under the body of the unit 23 along each edge where it is desired to secure the roofing unit to the roof. This folded under portion of the unit forms an anchoring strip through which ordinary attaching means, such as roofing nails, may be driven after the unit is laid in its final position. By folding the unit as at 31 along the line of the longitudinal slits 27, these slits sever or form a separation between the upper body and lower anchoring strip portions throughout a portion only of the finished or double thickness edge of the unit. These separations or longitudinal edge-slits together with the transverse slits 28-29 extending therefrom form flexible flaps that may be temporarily bent upwardly at a relatively obtuse angle to expose a section of the underlying anchoring strip, to and through which roofing nails, for example, may be driven into the building framework to anchor down the lower exposed edges of the units. When the nails have been driven into place then the flaps may be turned or pushed down over the temporarily exposed portion of the anchoring strip so that, although the unit is securely anchored near the butt or exposed lower edge, the nails are covered and there is no exposed metal.

It should be understood that in this operation it is not necessary to bend any portion of the shingle or unit which is actually relied upon to hold the shingle in place, but it is necessary merely to bend an auxiliary tongue or flap 26, the function of which is principally to cover and protect the securing nails 32 after they have been driven into place. In other words the fold or joining edge portions that interconnect the body and anchoring strip of a unit do not serve as a hinge but solely as a permanent and fixed connection therebetween.

After the nails 32 have been driven through the anchor strip 30, the flap 26 may be laid down flat against the anchor strip, but if necessary to secure further access to the nails, the tongue may be slightly bent up again as much as desired, without weakening the attachment of the shingle to the roof.

The roofing of the present invention is

preferably constructed of high grade felt, impregnated with asphaltum or other waterproofing composition, and covered on one side with a protective and decorative coating of granulated or flaked rock, such as slate. The folded portions or anchor strips 30 of the roofing are preferably formed, while the roofing is still hot, during the process of manufacture, as distinguished from folding

10 back a part of the roofing while it is cold, or just before its application to the roof. By producing the folds in the roofing while the roofing is still hot, the roofing units are not weakened at the point of the fold and it is 15 unnecessary subsequently to use as a hinge this fold or joining edge between the body and underlying anchor strip because the unit is not bent as a whole during any step of application to the building, and furthermore, 20 when constructed according to the present invention, the roofing units may be laid with a minimum expenditure of time and labor, since it is necessary only to bend up the flaps on the shingles and drive in nails in the usual manner of attaching wooden shingles.

The present shingles may also be laid by relatively unskilled labor, since all of the parts of the shingle will be intact and pre-formed, and ordinary roofing nails may be 30 employed as distinguished from the many complicated securing and interlocking devices used in the prior art.

It is of course understood that any roofing strip, such as the ridge strip 24, may be cut 35 off straight with ordinary cutting tools where necessary or desirable, as at the end of the ridge, and since all of the features of the present invention need not be employed in every embodiment, some forms of the shingle 40 units may be provided with ordinary straight ends, such as the unit shown in Fig. 9.

It is highly desirable, however, in the case of ridge, gutter and corner strips, that provision be made for the longitudinal overlapping 50 of the successive strips, and to provide for longitudinal overlapping without more than a double thickness at any point, the units 23 may have their ends formed as shown in Fig. 3. Thus the left hand end 55 of the unit 23 in Fig. 3 is provided with a pair of longitudinally extending portions 33 adjacent each edge of the pattern, the balance of the end 34 being cut straight across.

The longitudinally extending portions 23 55 are of substantially the same width as the portions 30 which are folded under the roofing unit 23, and consequently the roofing unit 23 will have a pair of longitudinally projecting exposed portions 33 adapted to be covered by adjacent tongues or bendable portions 26 upon the next ridge strip. This is best illustrated at the left end of the ridge strip 24 in Fig. 2.

At the opposite end of the roofing unit 23, 60 the unit is formed with the same flaps or

tongues 26 and sufficient of the folded portion 30 is cut away as at 35 so that when the edge 34 of the next strip is placed adjacent the edge or slit 29 of the end tongue 26, the longitudinally projecting portions 33 will 70 fill in the space 35. That is, the right hand end of the roofing unit is formed with a cut out portion 35 which is complementary to the tongue 33 at the left end:

The right hand end of the roofing unit 75 23 is also provided with a longitudinal extension 36 which is of less width than the balance of the roofing unit 23, the longitudinal extension or underlap 36 preferably being diminished in width by four times the width of the folded portion 30. This forms another rectangular cut out portion 37 adjacent the right hand end of the pattern in Fig. 3, but it will be noted that the only waste in cutting roofing units of the form shown in this figure, comprises the two small rectangular portions 35 and 37 which are cut out:

When the folded portion 30 of the roofing unit 23 is bent under the roofing along the line 25, the tongue 38 formed adjacent the 90

end corners of the roofing unit, is folded underneath the flap 26. The adjacent tongue or longitudinally projecting portion 33 of the next strip is also received beneath one of the tongues 26 at the right end of the strip, but due to the fact that the portion 35 is cut out, there will be no triple layer at this point, and the successive units may be joined together smoothly. The extension or underlap 36 will then be received below the straight 95 end 34 of the next strip, as shown in Fig. 2, but since the extension 36 is narrower than the balance of the unit as shown in Fig. 3, there will be no triple layer at the point 39 (Fig. 2), due to the cutting out of the portion 100 37. The flap 26 adjacent the end of the roofing unit 23 at the joint may be lifted and nails driven in the longitudinally extending tongues 33 and 38, thereby securing the ends of both units, the nails being covered by the 105 flap 26 in the usual manner.

It will thus be observed that in order to provide ridge, corner or gutter strips which may be laid smoothly without any triple layers, the ends of the roofing units may be 110 formed with folded portions which are substantially complementary to each other, with the exception of an overlapping portion adjacent the middle of the strip, and the successive strips are adapted to be attached to the roof by ordinary roofing nails, which are 115 protected from the weather by flaps of the same strip or an adjacent strip.

Where the units 23 are used for gutters, they will, of course, be laid first, and the 120 edges of the gutter strips will be overlapped and covered by adjacent shingles or other forms of roofing units employed to such an extent that the slits 25 are preferably completely covered by the courses of shingles 125

above the gutter, but it will be evident that the present mode of attachment and improved shingle construction is applicable to each of the forms of roofing strips provided 5 for attachment to angular surfaces.

Referring to Figs. 4, 5 and 6, the modification illustrated in these figures is peculiarly adapted to provide an additional feature which clearly enhances the appearance of 10 the roofing and adds to its salability. The ordinary asphaltum roofing is usually provided with an upper or outer surface 40 having a protective covering for the purpose of resisting the weather and giving the roofing 15 an attractive appearance, while the lower or inner surface 41 is ordinary given no especial finish, so that the lower surface shows the color of the waterproofing composition applied, which is generally black. The present 20 invention is adapted to utilize this feature of ordinary roofing, for the purpose of producing a shading effect as well as a color contrast adjacent the edges of certain portions of the roofing units, but it should be understood 25 that the invention is also applicable to special forms of roofing in which the color combinations or surfaces may be made of any desirable color or finish.

Thus, in the modified form shown in Fig. 30 5, the parts which correspond to the slits 28 and 29 of Fig. 3 have been widened to form slots 42 and 43 upon each side of a flap 44, corresponding to the flaps 26 of Fig. 3.

The rear surface 41 of the folded portion 35 or anchor strip 45 of the roofing unit is exposed at the slots 42 and 43 so that the flap 44 stands out in relief against the underlying contrasting colored portion 41.

The roofing unit 46 of this modified form is 40 also provided with longitudinally extending slits 47 at the base of the slots 42 extending to the right in Fig. 6 from slot 43 to slot 42, but the corresponding space extending to the 45 right from slots 42 to slots 43 is not cut but is utilized for producing a fold or joining edge at 48 for uniting and supporting the folded portion 45 to the body of the unit.

The fold 48 is especially located in this modified form to provide an additional contrasting or shaded portion below the bendable portions 44, and the slits on the outside edges of slots 42 and 43 relative to the tongues 44, are elongated at 49 and 50 to form an additional tongue 51 which is not folded back, but 55 which projects below the flap 44, forming a contracting or shading surface along the bottom edge of the flaps 44. The line of fold in this single unit is slightly below the slits 47, that is, on a line determined by the end of 60 the slits 49 and 50 so as to leave the tongue 51 projecting a greater distance below the flap 44.

In the present embodiment, it is of course 65 evident that some forms of the invention may have the ends of the unit cut in a straight

line, but this modified form is also preferably provided with ends which are complementary in form to the next adjacent units, so that the ends of one unit will overlap the folded portion of the next unit. Thus the left end 70 of the unit in Fig. 6 has a straight edge 52 on the body of the shingle, while the end 53 of the folded portion 45 is offset longitudinally by a distance 54 equal to half the width 75 of one of the flaps 44.

At the opposite end, the longitudinally projecting portion 55 of the folded portion or anchor strip 45 projects beyond the straight end 56 of the body of the roofing unit by a distance which is equal to the offset 54 at 80 the other end, so that successive units have complementary ends. The projecting portion 55 of the folded part 45 of the unit is thus covered by the opposite end of the body 85 of an adjacent similar shingle.

It will be evident that the flaps 44 may be bent up in the manner previously described, and nails driven through the folded back portion or anchor strip 45 in substantially the same manner described for the previous embodiment, laying the units from left to right in order that each successive unit may cover the projecting folded portion 55 and producing an effect such as that shown in Fig. 4.

The specific embodiment which has been chosen to illustrate this invention has slots or openings exposing contrasting portions of the lower surface of the roofing, to simulate shingles of rectangular form, but it should be understood that the slots may be made of any geometrical shape or ornamental appearance to produce the effect desired.

Referring to Figs. 7 and 8, the modified form here illustrated consists of individual shingles which are laid with their sides extending diagonally to the principal lines of the roof, and the invention is here applied to the corner of a roofing unit. In this embodiment the shingles are laid in courses in the manner of ordinary shingles of this shape, 105 overlapping as shown in Fig. 7, the shingles being preferably provided with a prefolded portion or anchor strip 57 at the lower corner, and with a slot 58 extending along the line of 110 fold to a pair of transverse slots 59 and 60. This forms a flap 61 similar in construction 115 to those previously described, so that the flap 61 may be bent upward and nails or other fastened means driven through the anchor strip 57 to secure the individual shingles in place. The overlapping of the shingles is 120 preferably such that the nails driven through the anchor strip also pass through portions of the shingles immediately below the shingle 62. The fold 63 is preferably formed at such a point that the length of the side 64 of the triangular folded portion or anchor strip 57 is equal to the amount of overlap 125 desired, so that the adjacent edges of the 130

shingles 65 and 66 lie against the edges of the anchor strip.

After the first course of shingles of this type has been laid, each of the shingles of the next course above may be located by merely placing the triangular shaped anchor strip in the corner provided by the edges of the two adjacent shingles 65 and 66 below the shingle to be placed, and the joint between the shingles is a triple joint at the anchor strip, but the folded portion 57 fills in the space beneath the shingle 62 at the point of overlap of the four shingles, so that the four shingles fit together smoothly at the corners of the shingles.

Referring to Figs. 9 and 10, the modified form here illustrated is provided with an opening 67 adjacent the lower edge for exposing a contrasting lower surface 68 of the folded back portion anchor strip 69. This single unit 70 is also provided with a pair of transversely extending slits 71 and 72 forming a flap 73 capable of being bent up to give access to the anchor strip so that the fastening nails may be driven throughout. The anchor strip is folded along the line of the lower side 74 of slot 67, so as to expose the contrasting surface 68 of the bottom of the roofing.

The shingles of the present embodiment may be laid in the manner of ordinary wooden shingles, with the joints broken as shown in Fig. 9, and it will be evident that the flap 73 may be bent up to secure the lower edge of the shingles by a plurality of nails or other fastening means 75 driven through the anchor strip 69, after which the flap 73 may be bent down to cover and protect the nails 75.

It should be noted that any of the novel features described herein may be applied to any of the forms of units mentioned herein, and the modified forms of Figs. 7, 8 and 9 may be applied to strip shingles, ridge

strips, or even rolls of roofing.

Referring to Fig. 11, the modified form here illustrated is one of the simplest types of shingles having one or more flaps 26 and a folded back portion or anchor strip 30.

Referring to Fig. 1, the roll roofing illustrated in this figure comprises ordinary roll roofing, one or more edges of which are provided with folded back portions or anchor strips 30 and with slits forming flaps 26.

It will be evident therefore, that the modified forms shown with respect to the ridge strip in Fig. 1 or the strip shingle in Fig. 5 may be embodied in individual shingles or in rolls of roofing, all of which are preferably, but not necessarily, prefolded, while the material of which the roofing is constructed is still hot, to save work in the application of the roofing, and to prevent any possibility of breaking of the roofing at the fold.

Some embodiments of the invention, how-

ever, may have the fold to form the anchor strip produced when the shingle is applied, provided the roofing is capable of permitting a fold without breaking, and some forms of the invention may include roofing peculiarly adapted to permit folding while cold. Of course the back-turned underlying portions of the units, i. e., the anchor strip through which the nails are driven to secure the units in place, may have holes preformed beneath the flaps for the reception of the nails, although usually the nails can be driven through the material without the necessity for preformed nail holes.

It will thus be observed that I have invented an improved roofing construction which is universally applicable to all of the forms of roofing units necessary in ordinary construction. My roofing units may be applied with a minimum expenditure of time and labor by the use of ordinary roofing nails, without employment of skilled labor, and without exposing any metal parts to the weather.

The present invention is capable of producing novel effects in the appearance of the roofing, which enhance its value and increase its salability, and the roofing is positively prevented from curling upward at the lower edge by a fastening means which is not weakened by the operation of attaching the roofing, since the bendable portion of the roofing is not depended upon for the securing function.

While I have illustrated a preferred embodiment of my invention, many modifications may be made without departing from the spirit of the invention, and I do not wish to be limited to the precise details of construction set forth, but desire to avail myself of all changes within the scope of the appended claims.

Having thus described my invention, what I claim is new and desire to secure by Letters Patent of the United States, is:

1. A roofing unit comprising a flexible sheet having an edge prefolded under said sheet for attachment to a roof by roofing nails or the like, said sheet having a bendable portion above said prefolded portion for access to said nails.

2. A roofing unit having a plurality of slits forming bendable portions, and having a portion of its edge folded under said bendable portions for attachment to the roof by concealed fastening means, said roofing unit having openings for exposing a contrasting part of said folded portion.

3. A roofing unit having an elongated opening adjacent an edge, a folded portion of said unit below said opening, exposing a side of contrasting color, and slits transverse to said edge for forming a bendable flap for covering fastening means on said folded portion.

4. A building covering unit comprising a

sheet of flexible prepared roofing material with a portion folded under along one edge of the body of the sheet, the folded under portion being severed from the body of the sheet along a part of the joining edge and the body of the sheet being cut inwardly from the edge at the severance to form a flap in the body of the sheet above the folded under portion whereby the folded under portion may be exposed for the application of means to attach the same to the building.

5. A building covering unit comprising a sheet of flexible prepared roofing material having a portion folded under along one edge to form an underlying anchor strip for attachment to the building, the body of the sheet and the anchor strip being severed from each other adjacent a part of the joining edge therebetween and the body of the sheet having a cut extending inwardly from the region where the body of the sheet is severed from the anchor strip, said severance and inwardly extending cut forming a flap in the body of the sheet above the anchor strip whereby the anchor strip may be temporarily exposed for the application thereto of means to attach the same to the building.

6. A building covering comprising a unit of flexible prepared roofing material having a body portion and a folded under anchoring portion, the fold between the body and anchoring portions constituting one edge of the unit, and a flap whereby the anchoring portion may be temporarily exposed for the application thereto of attaching means, said flap being integral with the body portion and formed therefrom by a separation between the body and anchoring portions along the fold between them and a cut extending inwardly of the body portion from the separation.

7. A building covering comprising a unit of flexible prepared roofing material having a body portion and a turned under anchoring portion, the body portion having an aperture through which fastening means may be applied to and through the anchoring strip into the building framework, and a flexible flap formed integrally with the body to cover the aperture and thereby conceal the fastening means.

8. A building covering unit comprising a sheet of flexible prepared roofing material having a retroverted portion to form an anchor strip for receiving attaching means to secure the unit in place, and means whereby the retroverted portion may be temporarily exposed for the application of the attaching means thereto while the unit is occupying its final position on the building.

9. A building covering unit comprising a sheet of flexible prepared roofing material folded to form a body portion and an underlying anchor strip, the anchor strip serving to receive attaching means to secure the unit

in place, and a flap formed integrally with the body portion and serving temporarily to expose the anchor strip so that the attaching means may be applied thereto.

10. A building covering unit comprising a sheet of flexible prepared roofing material folded to form a body portion and an underturned anchor strip, the body portion and anchor strip being separated from each other throughout a portion of the fold therebetween and the body portion having a cut merging with such separation to form a flap that may be raised to expose the anchor strip for the application of attaching means thereto.

11. A building covering unit comprising a sheet of flexible prepared roofing material permanently folded to form a body portion and an underlying anchor strip, said body portion being cut to form a flap that may be raised to expose the underlying anchor strip and may be laid down to cover the anchor strip.

12. A building covering unit comprising a sheet of flexible prepared roofing material, said sheet being folded to provide a turned under anchor strip at one edge, and cut to form easily movable flaps above the anchor strip whereby the anchor strip may be temporarily exposed for the application of nails thereto to secure the unit to a building.

13. A building covering unit comprising a sheet of flexible prepared roofing material folded to provide a turned under anchor strip at one edge of the unit and cut to form a movable flap in the sheet above the anchor strip whereby the anchor strip below the flap may be exposed for the application of fastening means to secure the anchor strip to a building, the cut serving permanently to expose the underlying anchor strip about a part of the flap.

14. A building covering unit consisting of a sheet of flexible prepared roofing material having contrasting front and rear faces, one edge of the sheet being folded back to form an anchor strip for receiving attaching means whereby the unit is secured in position on a building and so that the rear face of the sheet throughout the folded back portion lies facing the front of the unit, and the body of the sheet having an opening therethrough permanently to expose the contrasting rear face of the anchor strip and to form a loose flap which may be temporarily lifted to expose a part of the anchor strip lying thereunder to permit application of the fastening means to the anchor strip and which thereafter may be laid back upon the anchor strip to conceal the fastening means.

15. A building covering unit formed from a sheet of flexible prepared roofing material with contrasting front and rear faces, an edge of the sheet being folded back so that the rear face of the sheet throughout the

folded back portion lies facing the front of the unit and to form an anchor strip for receiving attaching means whereby the unit is secured in position on a building, the body of the sheet having an opening therethrough

5 to form a loose flap which may be temporarily lifted to expose the anchor strip immediately therebeneath for the application of attaching means to the anchor strip and 10 permanently to expose the contrasting rear face of the anchor strip adjacent an edge of the flap.

16. A building covering unit formed from an elongated sheet of flexible prepared roofing material having contrasting front and rear faces, one edge of the sheet being folded back to form an anchor strip for receiving attaching means whereby the unit may be secured in position on a building and so that 20 the rear face of the sheet throughout the folded back portion lies facing the front of the unit, the body of the sheet being provided with a plurality of openings forming spaced apart flaps which may be temporarily 25 raised for the application of fastening means to the anchor strip therebelow and permanently exposing the contrasting rear face of the anchor strip about margins of the flaps.

17. A building covering unit comprising 30 an elongated sheet of flexible prepared roofing material having contrasting front and rear faces, an edge of the sheet being folded back beneath the body of the unit to form an anchor strip by which the unit is anchored with attaching means applied through the anchor strip and into the building framework and the rear face of the portion of the sheet forming the anchor strip facing the front of the unit, the body of the unit adjacent the margin which is folded being provided with a series of spaced longitudinal openings and transverse openings merging into the longitudinal openings, the longitudinal and transverse openings forming a 40 series of spaced flaps overlying the anchor strip and exposing the contrasting rear face of the anchor strip about each flap, said flaps being movable temporarily to expose the anchor strip immediately therebeneath so that 45 attaching means may be applied to the anchor strip and subsequently to conceal the attaching means.

18. A building covering unit comprising a sheet of flexible roofing material having contrasting front and rear faces, the sheet adjacent one edge being folded back to form an anchor strip for receiving attaching means whereby the unit may be anchored in position on a building and so that the rear surface of 50 the portion of the sheet forming the anchor strip faces the front of the unit, the body of the unit having a slit parallel to the fold and a transverse slot adjacent each end of and merging with the slit to form a flap which 55 may be temporarily lifted to afford access to

the underlying anchor strip to permit the application of fastening means thereto and permanently to expose the rear surface of the anchor strip with its contrasting color beyond an edge of the flap. 70

In witness whereof, I hereunto subscribe my name this 18 day of April, 1929.

EDWARD ROSCOE BLACK.

CERTIFICATE OF CORRECTION.

Patent No. 1,802,868.

Granted April 28, 1931, to

EDWARD ROSCOE BLACK.

It is hereby certified that error appears in the printed specification of the above numbered patent requiring correction as follows: Page 5, line 114, claim 1, after the word "for" insert the word affording; and that the said Letters Patent should be read with this correction therein that the same may conform to the record of the case in the Patent Office.

Signed and sealed this 2nd day of June, A. D. 1931.
